COMPENSATING GOVERNOR CONTROLLED THROTTLE

Farrell D. Biddle, Milwaukee, Wis., assignor to
 Pierce Governor Company, Anderson, Ind., a
 corporation

Application July 30, 1942, Serial No. 452,883

8 Claims. (Cl. 123—108)

This invention relates to centrifugal governing of engines utilizing a combustible mixture either as a gasoline, or gas engine, or as a Diesel engine.

In the former engine the governing element is usually a butterfly valve, and in the latter engine it is a plunger, or rack. For illustration purposes, same herein is shown as of the former type.

In governing of the aforesaid character the control structure is directly responsive to engine speed, and in the type illustrated, static and velocity pressures on governing valves vary, so that the torque exerted thereon by fuel mixture flow through the engine intake varies for different speeds and loads, etc.

The chief object of this invention is to offset this uneven torque pressure on the governing throttle valve, so that the latter is truly directly and proportionally responsive to the centrifugal control imposed on said valve.

The result is that extremely close governor regulation between no load and full load is possible, because the torque reactions on said valve between these loads is properly compensated for.

The chief feature of this invention resides on the inclusion of governor valve torque pressure compensator in the form of a cam and follower structure that is arranged to impose a force on said valve at any position thereof substantially equal and opposite to the fuel mixture flow torque imposed thereon, with the result that there is in effect a negligible pressure result, or a pressure that is substantially constant for the full range of throttle valve travel.

Other objects and features of this invention will be set forth more fully hereinafter.

The full nature of the invention will be understood from the accompanying drawing and the following specifications and claims.

In the drawing,

Fig. 1 is a diagrammatic central sectional view of a conventional centrifugally operable device, a side elevation of a governor throttle body, the power connection therebetween and a side elevation of one form of compensating structure, parts being shown in the wide open throttle position, dotted lines indicating the fully closed throttle position.

Fig. 1A is an end view of Figure 1 showing the driving connection to the engine driven gear.

Fig. 2 is an end elevation of the throttle body with governor connection and compensating structure attached.

Fig. 3 is a valve position-torque-pressure curve for which compensation is provided.

Fig. 4 is an end elevation of a portion of slightly modified form of the invention.

In Fig. 1 of the drawing, 10 indicates a housing of a centrifugally operable structure secured to a portion of the engine by bolts 11 and having a lateral opening by which a gear 12, keyed at 13 to the centrifugal shaft 14, can engage and mesh with an engine, or engine driven gear, so that shaft 14 is rotatable at, or proportional to engine speed.

Shaft 14 is rotatably supported in anti-friction bearings 15 and 16, the latter being mounted in 10 in the housing extension 10a. Longitudinally slideable on, but rotatable with shaft 14, is sleeve 17. Rigid with shaft 14 is base 18, to which is pivoted at 19 the centrifugal force responsive weights 20, having tail or finger portions 21 positioned adjacent one end of sleeve 17.

At a predetermined engine speed, determinable by the load spring adjustment and spring selected, these weights, due to centrifugal force, tend to move outwardly and upon doing so, their tail portions 21 slide sleeve 17 upon shaft 14. Herein sleeve 17 is illustrated as mounting an anti-friction bearing member 22 at the end opposite the tail engageable portion.

A yoke lever pivoted at 23 has spaced portions 24 engageable by bearing 22. Thus the lever 25 is tiltable by weight movement responsive to centrifugal force. A load spring 26 bears at 27 upon lever 25, being retained thereon by stem guide 28. Housing 10 is threadedly apertured at 29 and an externally threaded socket type cap, having socket 30 and knurled head 32, seats the other end of said spring, and may be manually rotated, respectively, for adjusting the initial force of such load spring. Lock nut 31 holds the adjustment.

35 This spring normally opposes centrifugal movement of the weights at all times. When the centrifugal force is sufficiently great, the weights move, as described, and hence tilt lever 25. This is the control lever and is usually connected to 40 the governing member, such as a butterfly valve 40 in a passage 39 through a throttle body 38 in the engine intake system.

45 All of the aforesaid describes a conventional centrifugal governor, and in the present invention the same is not disturbed, but the effect of other forces, as initially described herein, are of such character that this theoretical operation is modified to that extent. The present invention automatically compensates for such forces, so that 50 the actual governing operation is substantially the theoretical operation.

55 Herein, see Fig. 1, lever 125 outside of the governor housing and rigid with shaft 23, supports a pin type end 33 of a rod 34, which may be adjustable length type. At its opposite end, this

rod is pivotally connected at 35 to a lever arm 36, rigid with an exposed end of throttle shaft 37, pivoted in throttle body 38 interposed in the engine intake system downstream of the carburetor and usually between the carburetor and engine manifold connecting flanges, see Fig. 1.

Herein shaft 37 projects through the body and on its other exposed end mounts another arm 41 pinned thereto as at 42. This shaft may be mounted in anti-friction bearings (not shown) and, for bearing insertion and mounting purposes, detachable cap 43 is provided, as shown.

The free end of arm 41 mounts on pivot 44, the roller or follower 45. An anti-friction race may be interposed between pivot 44 and roller 45 wherever desired or required and same can be of the character illustrated in Fig. 9 of Hufford Patent No. 2,287,036.

The aforesaid several anti-friction bearings broadly are so conventional to standard governor practice that the same are not illustrated in detail.

Pivotedly supported at 46 on the throttle body, and adjacent arm 41, is member 47. The roller and member 47 lie in a common plane and the face of member 47 confronting roller 45 is the cam face. It includes the reentrant portion 48, hump 49, and reentrant portion 50, these corresponding to certain range positions of the throttle valve 40, to-wit mostly closed, about half open and mostly open ranges respectively.

A spring 51, of light tension character, but of sufficient strength for the purpose desired, has one end secured at pin 52 to member 47 and the other end herein is shown secured at pin 53 to the arm 41. Either one of these anchorages may be of adjustable character for accurately adjusting this spring force and in a manner similar to anchorage 153 in Fig. 4 for the corresponding spring 51 in Fig. 1.

In Fig. 4, a modified form of the invention is illustrated. In said figure, like or similar parts bear numerals of the one hundred series, similar to primary numeral designating such parts on Fig. 1. This modification may be briefly dismissed with this observation: the spring 151, anchored to pivoted cam member 147 at 152, has its opposite end adjustably anchored to the throttle body 138 at 153. Operation of this form is substantially identical to that of the form illustrated in Figs. 1 and 2.

For a complete understanding of this invention reference must again be had to the cam and its correlation to the chart, see Fig. 3.

This chart is derived by actually testing the engine to which the invention is to be applied. By this, in mass production, is meant testing any representative engine. The last mentioned spring anchorage adjustment will be capable of adjusting any one of the same inventions to any particular engine.

The curve represents the pressure in inch pounds of torque imposed upon said valve shaft incident to fuel flow through the intake for different positions of said valve. The valve 40, it is to be noted, is centrally mounted, so that at closed throttle and wide open throttle, these forces on the valve are balanced and absent, or negligible respectively. Having obtained this curve, the cam is laid out so that proper compensating force is applied thereto with the result that over the entire range, from one extreme position to the other of the valve, the actual effect of such generated forces is negligible, or cancelled out.

It is here pointed out that the adjustable anchorage of the compensating spring in effect when changed merely is the equivalent of bodily raising and lowering the curve, or rather the increasing or decreasing, of the maximum compensating force, the modifications thereof occurring as before.

This compensating device is exceptionally simple in character and when applied to a conventional type centrifugal governor results in extremely close and accurate governor regulation, or in other words, the throttle valve has a tendency to blow open at all speeds and all loads when so compensated.

15 While the invention has been illustrated and described in great detail in the drawing and foregoing description, the same is to be considered as illustrative and not restrictive in character.

20 The several modifications described herein, as well as others, which will readily suggest themselves to persons skilled in this art, all are considered to be within the broad scope of this invention, reference being had to the appended claims.

25 The invention claimed is:

1. An engine governing mechanism having a fuel controlling member subject to a variable torque incident to variable fuel supply to the engine and a centrifugally operable structure, including a member movable responsive to engine speed, and a direct connection between said members for operating the former member by the latter for varying the fuel supply, including in combination means for compensating for the variable torque on the fuel controlling member.

2. An engine governing mechanism having a fuel controlling member subject to a variable torque incident to variable fuel supply to the engine and a centrifugally operable structure, including a member movable responsive to engine speed, and a direct connection between said members for operating the former member by the latter for varying the fuel supply, including in combination means for compensating for the variable torque on the fuel controlling member, said means including a spring and a cam and follower structure associated therewith for applying a cam determinable portion of the spring force as the torque compensating force, the cam face conforming generally to the valve position-pressure torque curve of the engine.

3. An engine governing mechanism having a fuel controlling member subject to variable torque incident to fuel supply to the engine, a centrifugally operable structure having a member movable responsive to engine speed, and a direct connection between said members for operating the former member by the centrifugally controlled member, said direct connection including means for substantially compensating for the aforesaid variable torque on said fuel controlling member, the centrifugally operable governor including a main load spring normally opposing any structure member movement responsive to centrifugal force until that force attains a predetermined amount and thereafter proportionally opposing said member movement.

4. An engine governing mechanism having a fuel controlling member subject to variable torque incident to fuel supply to the engine, a centrifugally operable structure having a member movable responsive to engine speed, and a direct connection between said members for operating the former member by the centrifugally controlled member, said direct connection including

means for substantially compensating for the aforesaid variable torque on said fuel controlling member, said means including a spring and a cam and follower structure associated therewith, for applying a cam determinable portion of the spring force as the torque compensating force, the cam face conforming generally to the valve position-pressure torque curve of the engine, the centrifugally operable governor including a main load spring normally opposing any structure member movement responsive to centrifugal force until that force attains a predetermined amount and thereafter proportionally opposing said member movement.

5. Centrifugal governing apparatus for an engine, including a fuel controlling member movable responsive to engine speed in accordance with centrifugal force proportional thereto, and a compensating means connected to said member and arranged for compensating for inherent variable torque imposed upon said member incident to fuel supply to the engine, including a

cam member, a follower member and a spring member, one of said cam and follower members being rigid with the fuel controlling member and movable therewith, the spring member being connected at one end to the other of said members and having its other end relatively stationarily mounted, the said other member being pivotally mounted.

6. Apparatus as defined by claim 5 characterized by the cam member being the pivotally mounted member.

7. Apparatus as defined by claim 5 characterized by the spring member being of tension type and the cam member being the pivotally mounted member.

8. Apparatus as defined by claim 5 characterized by the spring member being of tension type, and the cam member being the pivotally mounted member, the spring member being relatively 20 stationarily mounted on the controlling member.
